United States Patent Office

Des. 196,298
Patented Sept. 17, 1963

196,298

LAWN CHAIR

Frank W. Stevens, Rutherford, N.J., assignor to W. R. Grace & Co., New York, N.Y., a corporation of Connecticut

Filed Jan. 25, 1963, Ser. No. 73,317

Term of patent 14 years

(Cl. D15—1)

FIG. 3.

FIG. 2.

FIG. 1.

The dominant features of my design reside in those portions shown in full lines on the drawing.

I claim:

The ornamental design for a lawn chair, as shown and described.
